Primary Examiner—Ian Simmons*Assistant Examiner*—Dana Sipos(74) *Attorney, Agent, or Firm*—Lewis Anten; Ying Chen(57) **CLAIM**

The ornamental design for a toy bubble bottle, as shown.

DESCRIPTION

FIG. 1 is a front elevational view of a toy bubble bottle showing my new design;

FIG. 2 is a right side elevational view thereof;

FIG. 3 is a rear elevational view thereof;

FIG. 4 is a bottom plan view thereof; and,

FIG. 5 is a top plan view thereof.

The broken lines shown in the drawings are for illustrative purposes only and form no part of the claimed design.
